UNITED STATES PATENT OFFICE.

FRANK S. DOBSON, OF LAKE CRYSTAL, MINNESOTA.

TRENCH-EXCAVATING MACHINE.

1,237,310.

Specification of Letters Patent. Patented Aug. 21, 1917.

Application filed December 1, 1916. Serial No. 134,422.

To all whom it may concern:

Be it known that I, FRANK S. DOBSON, a citizen of the United States, residing at Lake Crystal, in the county of Blue Earth 5 and State of Minnesota, have invented new and useful Improvements in Trench-Excavating Machines, of which the following is a specification.

This invention relates to trench excavating machines and it consists in the novel 10 features hereinafter described and claimed.

An object of the invention is to provide a machine adapted to be used in soft or sandy soil for the purpose of cutting a 15 trench, the parts so arranged that as the trench is being cut the same may be walled up by using planking or other supports whereby the sides of the trench are prevented from caving in as the machine progresses.

With this object in view the machine includes a boom with means for raising and lowering the same. Chains are mounted for movement around rollers or drums located 25 at the opposite ends of the boom and suitable means are provided for rotating the upper roller. Plow points are carried by the chains and scrapers are mounted upon the chains between the said plow points. 30 Cutting blades are pivotally mounted upon the chains beyond the sides of the plow point and are adapted to swing in an outward direction as they move in an upward direction from the bottom of the trench and 35 the said blades are adapted to swing by gravity over the chains as they descend thereby providing space through which the planking may be inserted for the purpose of holding the side walls of the trench 40 against caving in as it is being cut.

In the accompanying drawing:

Figure 1 is a side elevation of the trench excavating machine;

Fig. 2 is a top plan view of the boom 45 thereof with parts in section.

Fig. 3 is a longitudinal sectional view of the boom;

Fig. 4 is a perspective view of a plow 50 point used on the machine.

Fig. 5 is a detailed perspective view of one of the links of one of the chains.

Fig. 6 is a perspective view of the scraper.

Fig. 7 is a perspective view of a scoop 55 used on the machine.

Fig. 8 is a perspective view of a blade used on the machine.

The machine comprises a frame 1 which is mounted at its forward portion upon steering wheels 2 and at its rear portion upon a tractor 3 of the caterpillar type. An 60 engine 4 is mounted upon the frame 1 and is operatively connected with the said tractor 3 by means of a chain 5.

A mast structure 6 is mounted upon the rear portion of the frame 1 and is provided 65 with suitable journaled pulleys 7. A shaft 8 is journaled upon the mast structure 6 and is rotated by means of a chain 9 which passes around a sprocket wheel 10 mounted on the said shaft and which in turn is operatively connected with the engine 4 in a suitable manner. A belt 11 is mounted for movement transversely across the rear portion of the frame 1 and is adapted to be operated from the shaft 8 by the means of 70 a chain 12 and suitable connecting wheels 75 as best shown in Fig. 1 of the drawing.

A scoop 13 is mounted at the rear end of the frame 1 and its rear end is adapted to trail along the surface of the ground. The 80 upper forward edge of the said scoop projects slightly over the rear edge of the belt 11 as shown in Fig. 1. A boom 14 is pivotally connected at its upper forward end with the shaft 8 and its lower end is adapted to be swung vertically. A cable 15 is connected at one end with the lower portion of the said boom and is trained over the pulleys 7 and arranged to wind upon a drum 16 mounted on the frame 1 and may 85 be used for raising and lowering the free end portion of the said boom. A shaft 17 is journaled for rotation at the lower rear end of the boom 14 and disks 18 are carried by the shaft 17. Similar disks 19 are 90 mounted upon the shaft 8 and the disks 18 and 19 are in alinement with each other. Chains 20 are trained around the alined disks 18 and 19 and are arranged to move along the boom 14 when the shaft 8 is rotated.

Some of the links of the chains 20 are connected together by means of rods 21 and plow points 22 are supported at rear portions upon the said rods. Rods 23 are also 105 connected with some of the links of the said chains and pass transversely through the forward portions of the said plow points. The said plow points are approximately V-shaped in plan and their pointed ends are 110 adapted to penetrate in the ground during the operation of cutting the trench. Scraper

blades 24 are mounted upon the chains 20 at the points between the said plow points and are disposed transversely with relation to the said chains. The links of the chains 5 to which the rear portions of the plow points 22 are attached are designated as 25 and one of the said links is shown in Fig. 5. Cutting blades 26 are pivotally mounted upon the links 25 and are adapted to swing in planes parallel with the runs or sides of the chains 20. The links 25 are provided at their outer edges with outstanding lugs 27 and at their inner edges with outstanding lugs 28. The lugs 27 are located in the vicinity 10 of the point of pivotal connection between the said links and the cutting blades and are adapted to limit the outward swinging movement of the blades while the lugs 28 are located more remote from the point 15 of pivotal connection between the blades and the said links and are adapted to limit the swinging movement of the blades.

As the plow point 22 and the scrapers 24 move in an upper direction under the boom 25 14 they encounter the earth and the said points loosen the earth which is caught up by the scrapers and carried into the scoop 13. After a certain quantity of earth has been accumulated in the said scoop and as 30 additional quantities are supplied thereto the earth is forced from the scoop up over the upper edge thereof and deposited upon the upper run of the belt 11 which carries it to one side of the machine and dumps it 35 at the surface of the ground. When the blades 26 pass under the shaft 17 and come in contact with the earth they are swung outwardly at their free ends until their outer surfaces come in contact with the forward 40 end of the lugs 27. Thus the said blades cut the earth beyond the sides of the chains 20 and the earth so loosened is directed in an

inward direction and is caught up by the scrapers and carried to the scoop 13 as hereinbefore described. When the cutting blades 45 26 pass over the shaft 8 their free ends swing in inward directions by gravity until the sides of the said blades encounter the sides of the lugs 28 and thus the said blades 26 as they move in a downward direction 50 along the upper edge of the boom 14 are swung in beyond the outer side edges of the chains 20 and therefore planking or other similar material may be applied to the side walls of the trench along the upper runs of 55 the chains 20 and thus prevent the walls from caving in while the trench is being cut. Thus it will be seen that the machine may be used to advantage for digging a trench in soft ground in quick sand in view of the 60 fact that the walls of the trench may be braced in close proximity to the points in the earth where the cutting operation takes place.

Having described the invention what is 65 claimed is:—

1. In a machine of the character described, a boom, chains mounted for movement along the boom, plow points carried by the chains, and cutting blades pivotally mounted upon the chains at the opposite sides of the plow points and adapted to swing transversely of the chains.

2. In a machine of the character described, a boom, chains mounted for movement along the boom, plow points mounted upon the chains, cutting blades pivotally mounted upon the chains for swinging movement transversely thereof and lugs mounted upon the chains at the opposite sides of the said cutting blades and adapted to limit the swinging movement thereof.

In testimony whereof I affix my signature.
FRANK S. DOBSON.
